UNITED STATES PATENT OFFICE.

FREDERICK H. McDEVITT, OF WINTHROP, MASSACHUSETTS, ASSIGNOR TO THE STAFFORD COMPANY, OF READVILLE, BOSTON, MASSACHUSETTS, A CORPORATION OF NEW JERSEY.

FILLING-FEELER DEVICE FOR LOOMS.

1,237,923.

Specification of Letters Patent. Patented Aug. 21, 1917.

Application filed February 16, 1915. Serial No. 8,593.

To all whom it may concern:

Be it known that I, FREDERICK H. McDevitt, a citizen of the United States, and resident of Winthrop, county of Suffolk, 5 Commonwealth of Massachusetts, have invented an Improvement in Filling-Feeler Devices for Looms, of which the following description, in connection with the accompanying drawings, is a specification, like 10 characters on the drawings representing like parts in each of the several views.

The invention has relation to filling feeler devices of the class employing a slotted bobbin, and is applicable in those cases in which 15 the loom shuttles that are employed are furnished with spindles on which the filling-bobbins are mounted for the weaving operation. The object of the invention is to provide simple, efficient, and inexpensive means 20 of causing the lateral slot of a bobbin to register properly with the feeler slot in the front wall of the shuttle when the bobbin is in place within the shuttle. The invention consists, essentially, in coöperative 25 means in connection with the shuttle-spindle and bobbin for holding the bobbin on the spindle with its feeler-slot in register with that of the shuttle.

The invention will be better understood 30 from the following detailed description taken in connection with the accompanying drawings and will be thereafter pointed out in the appended claims.

Referring to the drawings:

35 Figure 1 is a plan view of a shuttle with a bobbin therein with my invention embodied in connection therewith, a fragment of a feeler member being also indicated;

Fig. 2 is a side elevation of the shuttle 40 with its spindle, a part of the shuttle body being broken away to better show a feature of the invention;

Fig. 3 shows in side elevation a bobbin constructed in accordance with the invention;

Fig. 4 is an enlarged end view thereof looking at the head of the bobbin;

Fig. 5 is an enlarged transverse section on line 5—5 of Fig. 3; and

50 Fig. 6 is a fragmentary section on line 6—6 of Fig. 4.

A shuttle of ordinary form is indicated at 10 with a spindle 11 pivotally mounted thereon at 12. The shuttle has a lateral feeler- 55 slot 13 in its front wall through which the

feeling end of a feeler 14 enters as the lay beats up with the shuttle in the shuttle-box at the side of the loom at which the feeler is located. The bobbin is formed near its head with the lateral feeler-slot 16. In order that when the bobbin is in working position on the spindle 11 the slot 16 shall be in alinement with the feeler-slot 13 and the feeler 14 as the latter enters therethrough the head of the bobbin 15 is provided with 60 a transverse slot 17 adapted to receive a pin 18 projecting transversely from the spindle 11 near the back thereof. This pin is so mounted on the spindle, and the slot 17 is so formed with reference to the slot 16, that 65 the bobbin will, in all cases when in working position on the spindle with the pin 18 engaging the notch 17, be positioned so that the slot 16 will be in alinement with the feeler; thus while for the bobbin shown the 70 pin 18 would be upright on the spindle, for left hand shuttles, the pin would be positioned underneath the spindle as indicated at 18'. In this way all the bobbins may be 75 made uniform, with the slots 16 and 17 80 therein relatively positioned exactly the same in all cases, and as regards the shuttles, the only differential requirement is that for right hand shuttles the pins 18 should extend from one side thereof, while for left hand shuttles 85 such pins should extend in the opposite direction. I preferably equip the head of the bobbin with a metallic ferrule 19 turned over the end of the bobbin as seen at 20 and the slot 17 can be conveniently cut in said 90 ferrule which latter is adapted to preserve the outline of the slot intact. I do not desire to be limited to the precise details of construction herein shown which are to be considered as illustrative and not restrictive 95 and I therefore refer to the appended claims rather than to the foregoing description to indicate the scope of the invention.

Having described my invention, what I claim as new and desire to secure by Letters 100 Patent is:

1. The combination with a shuttle having a spindle therein and a bobbin equipped with a lengthwise extending lateral slot adapted to be fitted on said spindle, of coöperative 105 means on the bobbin and spindle adapted to locate said slot in a definite angular position with reference to the shuttle.

2. The combination with a shuttle having a spindle hinged therein and a bobbin hav- 110

ing a lengthwise slot near its head, of co-operative means on said spindle and said bobbin for holding the bobbin in a definite angular position on the spindle for the purpose stated, said means consisting in a transverse pin and slot, one on the spindle and the other on the bobbin.

3. The combination with a shuttle having a spindle hinged therein and a lengthwise extending feeler receiving opening in its side, and a bobbin having a lengthwise extending slot near its head, of means for holding said bobbin so that said lengthwise extending slot is alined with said feeler receiving opening of the shuttle, said means consisting in a transverse slot at the head of the bobbin, and a transverse pin on the spindle adapted to engage in said slot.

4. The combination with a shuttle having a spindle hinged therein and formed with a 20 feeler receiving opening in a vertical side thereof, and a bobbin adapted to fit said spindle with a lengthwise extending slot near its head, of co-operative means on the bobbin and spindle for holding the bobbin on the spindle 25 with its lengthwise extending slot in alinement with said feeler receiving opening of the shuttle.

In testimony whereof, I have signed my name to this specification, in the presence of 30 two subscribing witnesses.

FREDERICK H. McDEVITT.
